Primary Examiner — Marianne N Pandozzi*Assistant Examiner* — Jae Liang(74) *Attorney, Agent, or Firm* — Edwin H. Crabtree; Ramon L. Pizarro(57) **CLAIM**

An ornamental design for a one gallon water bottle, as shown in the drawings and described in the specifications.

DESCRIPTION

FIG. 1 is a side perspective view of a one gallon water bottle showing my new design;

FIG. 2 is an opposite side perspective view of the one gallon water bottle;

FIG. 3 is a front perspective view of the one gallon water bottle;

FIG. 4 is a top view of the one gallon water bottle; and,

FIG. 5 is a bottom view of the one gallon water bottle. The surface pattern in the drawings depicts contrast in appearance.
